Primary Examiner — Richard E Chilcot*(74) Attorney, Agent, or Firm* — CIONCA IP Law P.C.(57) **CLAIM**

The ornamental design for a motor frame for submersible pump, as shown and described.

DESCRIPTION

FIG. 1 is a top view of a motor frame for submersible pump showing the new design;

FIG. 2 is a bottom view thereof;

FIG. 3 is a front elevation view thereof;

FIG. 4 is rear elevation view thereof;

FIG. 5 is a left side elevation view thereof;

FIG. 6 is a right side elevation view thereof;

FIG. 7 is a cross-sectional right side view thereof, taken along the vertical center of the motor frame; and,

FIG. 8 is cross-sectional front view thereof, taken along the vertical center of the motor frame.
